Attn.

UNITED STATES PATENT OFFICE.

FREDERIC AUMONIER, OF LONDON, ENGLAND.

DESIGN FOR WALL-PAPER.

SPECIFICATION forming part of Design No. 22,802, dated September 26, 1893.

Application filed August 28, 1893. Serial No. 484,263. Term of patent 3½ years. Patented in England March 3, 1893, No. 208,519.

To all whom it may concern:

Be it known that I, FREDERIC AUMONIER, (trading as WM. WOOLLAMS & Co.,) a subject of the Queen of Great Britain, and a resident 5 of 110 High Street, near Manchester Square, London, England, have invented a new and original Design for Wall-Paper, (patented in Great Britain on the 3d day of March, 1893, No. 208,519,) of which the following is a specification.

This design for wall paper and frieze is represented on the annexed drawing. The filling consists of acanthus treated in a new form of interlacing scrolls. The frieze is

formed of interlacing scrolls of acanthus with 15 a filling in of Tudor rose the beading running through the acanthus leaves.

I claim—

The design for wall paper substantially as shown and described.

FREDERIC AUMONIER.
